H. BAIN.

UNDERGARMENT CLASP.

APPLICATION FILED FEB. 24, 1920.

1,438,354.

Patented Dec. 12, 1922.

UNITED STATES PATENT OFFICE.

HENRY BAIN, OF CHICAGO, ILLINOIS.

UNDERGARMENT CLASP.

Application filed February 24, 1920. Serial No. 380,640.

To all whom it may concern:

Be it known that I, HENRY BAIN, a citizen of the United States, residing at the city of Chicago, in the county of Cook and State of Illinois, have invented certain new and useful Improvements in Undergarment Clasps, of which the following is a specification.

This invention relates to improvements in undergarment clasps for supporting hose, tucks in shirt sleeves for shortening their length, etc., and particularly those which, for their attachment, have heretofore required that they penetrate the fabric and that they be suspended in their operative position from an elastic band surrounding the limbs of the wearer, which are of undesirable thickness and lacking in flatness to the discomfort of the wearer.

The object of my invention broadly stated, is an undergarment clasp adapted to be secured in its operative position without penetrating the fabric of the undergarment, and which will reduce to a minimum the heretofore tendency of such a clasp to strain or tear the fabric of the garment and garments to which it is secured, and which is so constructed that it will be and lie flat against the garment without discomfort to the wearer.

A further object of my invention is a garment clasp, simple and cheap in construction, of the fewest number of parts consistent with its strength and capability of being secured to the garment without liability to accidental detachment therefrom, and which may be quickly attached to and removed from the garment and garments of the wearer.

With these ends in view, my invention finds embodiment in certain features of novelty in the construction, combination and arrangement of parts by which the said objects are attained, all as hereinafter fully described with reference to the accompanying drawings and more particularly pointed out in the claims.

In said drawings,

Fig. 1 is a front elevation of a clasp in which my invention finds its embodiment, illustrating its adaptability for use in connection with an elastic band surrounding the limb and limbs of the wearer.

Fig. 2 is a front elevation, illustrating means for connecting a pair of clasps of my invention for supporting the one garment

from another, in the absence of the use of a band for surrounding the limbs of the wearer.

Fig. 3 is a similar view, on a larger scale, showing my clasp in its operative position upon a hose suspended therefrom.

Fig. 4 is a longitudinal section taken on the line 4—4 of Fig. 3.

Fig. 5 is a similar view indicating the position of the clamping jaws relative to the suspended fabric, preceding their locking engagement.

Fig. 6 is a similar view, illustrating the operative position of the clamping jaws in locked engagement with a hose or other garment.

Fig. 7 is a transverse section taken on line 7—7 of Fig. 3; and

Fig. 8 is a front elevation of the clasp in its locked engagement with a hose or other garment.

Similar characters of reference indicate the same parts in the several figures of the drawings.

The clasp of my invention comprises an open frame consisting of side bars 9—9 and end bars 10 and 11, of elongated rectangular form, but may have its side bars extend along converging lines for gradually narrowing it towards one end, as illustrated in the figures of the drawings, except, possibly, Fig. 8, wherein the side bars 9—9 are substantially parallel, the frames in both instances being preferably formed by bending it from one piece of wire held together at its meeting ends by a cross-bar 18 herein-after referred to.

Pivoted to the end bars 10 and 11, respectively, are jaws 12 and 13, preferably of bladelike form, and which, for convenience of description hereafter, are respectively referred to as a "long jaw" and a "short jaw", owing to the difference in their length, both of which jaws are flat and of a width somewhat less than the distance between the side bars of the clasp, and are preferably made of thin sheet metal, bone, celluloid or ivory, but may be of wood and, for ornamental purposes, if desired, stained, painted or enameled to conform to the color of the garment to be supported or from which the clasp is suspended, and it would be no departure from my invention to provide the frame and jaws with a textile or leather cover stitched or cemented thereto.

The jaws 12 and 13 are respectively piv-

oted to the end bars 10 and 11 and preferably by means of lateral perforations 14 and 15, through each jaw, providing for sleeving them on the wire for the frame before bending it to form.

For suspending the clasp in its operative position, the jaw 12 is provided with transverse perforations 16-16 for stitching or riveting it to a tape 17, as indicated in Figs. 10 and 2, which may be non-elastic when the clasp is connected with an elastic band surrounding the limb of the wearer, which, however, preferably consists of an elastic tape when two clasps are connected, as 15 shown in Fig. 2 and indicated in the remaining figures of the drawing.

The oscillating movement of the jaw 13 is limited by a cross-bar 18 secured at its opposite ends to the side bars 9-9 of the 20 clasp, and which operates as a stop, preventing the smaller jaw 13 from moving beyond the operative plane of the longer jaw, for facilitating the engagement of the shorter jaw when moving it to a position for clamping the fabric 19 between the two jaws, as 25 will presently be explained.

The jaws 12 and 13, adjacent their free ends, are preferably beveled, as indicated at 18^a and 19^a, respectively, so that when 30 swung to their operative position, their inclined surfaces will lie in parallel planes, that the shorter jaw may operate (see Fig. 6) to provide a reverse fold in the fabric for locking it in its operative position.

35 In operation, for the suspension of hose, for example, from the drawers of the wearer, the longer jaw 12 is projected inwardly of and somewhat below the top edge of the hose, as indicated in Figs. 4 and 5, 40 with the shorter jaw held in the position shown in Fig. 4, whereupon the longer jaw is then pushed through the frame slightly beyond the same, followed by swinging the shorter jaw to its operative position, and 45 then pressing the longer jaw inwardly towards the shorter jaw until its further movement is resisted by the shorter jaw, and the shorter jaw has forced the fabric inwardly over the inclined surface of the 50 longer jaw, as shown in Fig. 6, and formed a crimp in the fabric between the opposing jaws, operating to maintain both jaws in their operative position and the fabric from accidental detachment therefrom.

55 It is now to be observed that the sides of the longer jaw diverge from its pointed pivot to its free ends and that, therefore, the greater the pull upon the fabric, the more firmly it will be held against slipping 60 off this jaw, and this even though it may not be pinched tightly between the side edges of the jaw and the frame. In this connection it is proper to note that the shorter jaw corresponds in width with the 65 opposing end of the longer jaw.

Between the wedging action of the fabric on the longer jaw and the fold formed over the end of this jaw by the shorter jaw, there can be, in ordinary use, no strain upon the fabric tending to puncture or tear it, or which will enable it to escape the grip of the jaws until the longer jaw with the fabric is swung outwardly beyond the frame, followed by swinging the shorter jaw away from its locking position, and then pushing the longer jaw inwardly and past the frame to the position shown in Fig. 4.

For securing the clasp to the slack in underwear, from which to suspend hosiery, 80 the same operation of the jaws shown at the upper end of Fig. 2 is followed; but when the hose is to be suspended from an elastic band passing around the limb of the wearer, as shown in Fig. 1, but one clasp is 85 necessary.

For connecting opposing plaits formed in shirt sleeves for shortening them, the jaws are preferably connected by an elastic tape, 90 as shown in Fig. 2, the manipulation of the jaws for clasping the plaits being precisely the same as that for securing one of the jaws to underwear and the other to hosiery suspended therefrom.

By the use of a wire frame and flat jaws pivoted to the end bars thereof, as I have 95 shown and described them to be, my invention provides an effective clasp for underwear, not only of a minimum number of parts, cheap of construction and effective in 100 operation, but a clasp so thin that it will lie flat upon the opposing flesh of the wearer and without presenting projections or thickness, tending to cause discomfort to the 105 wearer.

As a means for increasing the capacity of the clasp for several thicknesses of fabric, due to numerous folds for plaits therein, the longer jaw 12 may have its edges cut away, as indicated at 20-20 in Fig. 3, thereby increasing the space between the longitudinal edges and the frame accordingly for the purposes of greater thickness of fabric between these two members.

Having described my invention, what I 115 claim and desire to secure by Letters Patent is:

1. An undergarment clasp, consisting of an open frame, rigid clamping jaws one end of each of which jaws is pivoted directly to 120 said frame, one of which jaws is movable through the opening in said frame to a clamping position.

2. An undergarment clasp, consisting of an open frame, rigid clamping jaws one end 125 of each of which jaws is pivoted directly to said frame, both of which jaws are movable through the opening in said frame to their clamping position.

3. An undergarment clasp, consisting of 130

an open frame, rigid clamping jaws movable through the frame pivoted at one end to said frame with their free ends overlapping each other in their clamping position.

5 4. An undergarment clasp, consisting of an open frame, rigid clamping jaws one end of each of which is pivoted to said frame, the free ends of both of which jaws are beveled, overlapping each other, and being 10 adapted to directly contact with the material clamped between them.

5 5. An undergarment clasp consisting of a frame, jaws pivoted at one end to opposite sides of said frame, the free ends of which 15 are beveled and overlap each other in their operative position.

20 6. An undergarment clasp consisting of an open frame, jaws pivoted to two of the opposing side bars of said frame, and a stop limiting the pivotal movement of one of said jaws.

25 7. An undergarment clasp consisting of an open continuous wire frame, a pair of jaws pivotally sleeved adjacent one end upon opposing side bars of said frame, the free 30 ends of which jaws overlap each other in their operative position.

35 8. An undergarment clasp consisting of an open frame, a pair of jaws respectively pivotally connected at their outer ends with said frame, and adapted to overlap each other at their inner ends, the side edges of one of which jaws diverge from its pivotal support to its free end for the purposes de-

scribed.

9. An undergarment clasp consisting of a wire frame, flat sheetlike jaws pivotally

sleeved adjacent one end on the opposing end bars thereof, the free ends of which are beveled and are adapted to overlap each other in their operative clamping position, the side edges of one of which jaws diverge substantially from its pivotal point towards the free end thereof, and the width of which at its free end corresponds with that of the 45 free end of the other jaw.

10. An undergarment clasp consisting of an open wire frame, jaws pivotally sleeved on said frame, one of which is longer than the other and diverges outwardly at its 50 edges towards its free end, a stop for and limiting the movement of the shorter jaw, both of which said jaws are provided adjacent their free ends with opposing beveled surfaces whereby in their operative position 55 upon a fabric the fabric is held against slipping longitudinally on the longer jaw, and a crimp is formed in the fabric adjacent their free ends locking it against lateral displacement from between the jaws. 60

11. An undergarment clasp consisting of a continuous substantially rectangular frame formed of wire bent to form, opposing jaws sleeved upon the end bars of said frame towards their outer ends, provided at their 65 inner ends with opposing beveled surfaces adapted to overlap each other in their operative position, the side edges of one of which jaws diverge from its pivotal support towards the free end thereof, said frame being provided with a cross-bar forming a stop 70 limiting the pivotal movement of the shorter jaw. 70

HENRY BAIN.
